UNITED STATES PATENT OFFICE

CHARLES W. BRABBÉE, OF BRONXVILLE, AND BERNHARD GOERG, OF MOUNT VERNON,
NEW YORK, ASSIGNEES TO AMERICAN RADIATOR COMPANY, OF NEW YORK, N. Y.,
A CORPORATION OF NEW JERSEY

BOILER

Application filed November 10, 1931. Serial No. 574,190.

Our invention relates to improvements in heating apparatus, and the same has for its object to provide a boiler for domestic heating purposes which is simple in construction, efficient in operation and comparatively inexpensive to manufacture.

Further, said invention has for its object to provide a horizontal sectional boiler in which the currents of heated and cooler water will be duly separated and given positive direction of flow in order to effect the efficient circulation of the water.

Further, said invention has for its object to provide a boiler in which the flow of the water currents will be materially accelerated, and the "pick-up" capacity of the boiler greatly increased.

Further, said invention has for its object to produce a boiler in which the currents of hot water are caused to ascend at one side of the boiler while the cooler currents are caused to descend at the opposite side of the boiler and be carried to the base of the boiler, and there caused to flow across the same to the opposite side thereof.

Further, said invention has for its object to provide a boiler capable of maintaining a true and constant water line, and of delivering dry steam at the nozzle.

Other objects will in part be obvious and in part be pointed out hereinafter.

To the attainment of the aforesaid objects and ends our invention consists in the novel features of construction, and in the combination, connection, and arrangement of parts hereinafter more fully described and then pointed out in the claims.

In the accompanying drawings wherein like numerals of reference indicate like parts:—

Figure 1 is a side elevation illustrating one form of horizontal sectional boiler constructed according to, and embodying our said invention;

Fig. 2 is a detail side view of the boiler looking in the direction of the arrow *a*, Fig. 1;

Fig. 3 is a central vertical section of the boiler;

Fig. 4 is a transverse section taken on the line 4—4 of Fig. 2, and

Fig. 5 is a similar section taken on the line 5—5 of Fig. 2.

In said drawings 10 designates a boiler of the horizontal, sectional type generally used for domestic heating purposes. The boiler comprises a top or steam dome section 11, an intermediate section 12, and a relatively deep lower or fire-pot section 13. The several sections are supported upon an ash-pit section 14. The several sections are respectively provided with openings having doors 11^a, 12^a, 13^a and 14^a.

The adjacent faces of the several sections are provided at opposite sides of the boiler with registering nipple ports, and within the ports at one side are secured nipples 15 which constitute the sole passage for the ascending currents of heated water, and within the ports at the opposite side of the boiler are disposed nipples 16, 17. The nipple 16 serves to connect the top or steam dome section 11 with the intermediate section 12, and has a relatively short tubular portion 16^a, of slightly smaller diameter than its nipple portion, extending into said intermediate section and terminating adjacent to, but free of the base of said intermediate section. The nipple 17 is located directly below and in line with the nipple 16 and its tubular portion 16^a, and serves to connect the intermediate section 12 with the fire-pot section 13. The said nipple 17 has a relatively long tubular portion 17^a, of slightly smaller diameter than its said nipple 17, extending downwardly between the inner and outer walls of the fire-pot section, and has its lower free end terminating adjacent the base of the fire-pot section.

In order to accommodate the tubular portion 17^a depending from the nipple 17, the inner wall portion 18 of the fire-pot section is provided with a vertical, transversely-curved portion 18^a which extends inwardly into the fire-pot, and the corresponding part of the outer wall portion 19 is provided with a similar portion 19^a which extends outwardly beyond the circular contour of the fire-pot section thus providing an enlarged chamber portion 20 of greater internal diameter than the tubular portion 17^a which extends into

the same so that said tubular portion shall be protected against the direct heat of the incandescent fuel by the surrounding mass of water.

5 In order to insure the delivery of dry steam at the nozzle, and to prevent the heated water being immediately drawn into the accelerating means 16, 17, the steam dome is provided with a curved baffle plate 21, above 10 the point where the descending water currents enter the accelerating tubes.

The operation of the boiler will be largely obvious from the foregoing description. It need merely be noted that only two passages 15 are provided for the flow and return of water, viz: the nipples 15 at one side for the ascending currents of heated water, and the accelerating means 16, 16^a, 17, 17^a at the opposite side which serve to cause the cooler 20 water to pass from the upper or steam dome section 11 into the nipple 16 and its short tubular portion 16^a, and also from the intermediate section 12, entering between the lower end of the short tubular portion 16^a 25 and the nipple portion 17 connecting the intermediate sections 12 with the fire-pot section 13, and that the descending water is then carried downwardly by the tubular portion 17^a and finally discharged from the 30 lower end of said tubular portion and into the fire-pot section at the base thereof. The water is then caused to pass around said base to the opposite side of the boiler where, as the same becomes again heated, it will rise 35 together with the entrained steam and pass upwardly to the steam dome 11 by way of the nipples 15, and thus maintain a rapid and uniform circulation of water, and a steady water line in the gage glass.

40 It is to be noted that in order to obtain the most efficient circulation and acceleration of water flow, the tubular member 17^a should be substantially coextensive in length with the height of the fire-pot section, and that 45 sufficient space should be provided between the lower or outlet end of the tubular portion 16^a of each nipple 16 of the several sections, and the entrance end of the nipple portion next below in order to induce the flow of the 50 cooler descending water current into the latter-named nipple portions.

Having thus described our said invention, what we claim and desire to secure by Letters Patent is:

55 1. A horizontal sectional boiler comprising a relatively-deep fire-pot section, and at least one upper section thereon, nipple ports at opposite sides of boiler in the opposing faces of said sections and a nipple secured in 60 the ports at one side of the boiler and constituting the sole passage for the ascending currents of heated water, and water-accelerating means disposed in the nipple ports at the opposite side of the boiler; said means comprising a nipple portion uniting said up-

per section with said fire-pot section, and a tubular portion substantially coextensive in length with the height of said fire-pot section extending from said last-named nipple portion into said fire-pot section and having its free end terminating adjacent the base of said fire-pot section, substantially as specified. 70

2. A horizontal sectional boiler comprising a relatively-deep fire-pot section, and at least one upper section thereon, nipple ports at opposite sides of boiler in the opposing faces of said section and a nipple secured in the ports at one side of the boiler and constituting the sole passage for the ascending currents of heated water, and water-accelerating means disposed in the nipple ports at the opposite side of the boiler; said means comprising a nipple portion uniting said upper section with said fire-pot section, and a tubular portion of smaller diameter than said nipple portion and substantially coextensive in length with the height of said fire-pot section extending from said last-named nipple portion into said fire-pot section and having its free end terminating adjacent the base of said fire-pot section, substantially as specified. 80

3. A horizontal sectional boiler comprising a relatively-deep fire-pot section, an intermediate section and a top section, nipple ports at opposite sides of boiler in the opposing faces of said sections and nipples secured in the ports at one side of the boiler and constituting the sole passage for the ascending currents of heated water, and sectional water-accelerating means disposed in the nipple ports at the opposite side of the boiler constituting the sole passage for the descending currents of colder water; said means comprising a nipple portion uniting said top section with said intermediate section, and a relatively short tubular portion depending from said nipple portion, and a second nipple portion uniting said intermediate section with said fire-pot section, and a tubular portion substantially coextensive in length with the height of said fire-pot section extending from said last-named nipple portion into said fire-pot section and having its free end terminating adjacent the base of said fire-pot section, substantially as specified. 90

4. A horizontal sectional boiler comprising a relatively-deep fire-pot section, an intermediate section and a top section, nipple ports at opposite sides of boiler in the opposing faces of said sections and nipples secured in the ports at one side of the boiler and constituting the sole passage for the ascending currents of heated water, and sectional water-accelerating means disposed in the nipple ports at the opposite side of the boiler and constituting the sole passage for the descending currents of colder water; said means comprising a nipple portion uniting said top section with said intermediate section, and a 100

5 relatively short tubular portion depending from said nipple portion, and a second nipple portion uniting said intermediate section with said fire-pot section, and a tubular portion of smaller diameter than its said nipple portion and substantially coextensive in length with the height of said fire-pot section extending from said last named nipple portion into said fire-pot section and having its free end terminating adjacent the base of 10 said fire-pot section, substantially as specified.

5. A horizontal sectional boiler comprising a relatively-deep, double-walled fire-pot section having its adjacent inner and outer wall portions respectively provided with inwardly and outwardly extending transversely-curved vertical projections forming an enlarged chamber portion therebetween coextensive in height with said fire-pot section, 15 an intermediate section and a top section, nipple ports at opposite sides of boiler in the opposing faces of said sections and nipples secured in the ports at one side of the boiler, 20 constituting the sole passage for the ascending currents of heated water, and sectional water-accelerating means disposed in the nipple ports at the opposite side of the boiler constituting the sole passage for the descending currents of colder water; said accelerating 25 means comprising a nipple portion uniting said top section with said intermediate section and a relatively-short, tubular portion depending from said nipple portion, and 30 a second nipple portion uniting said intermediate section with said fire-pot section, and a tubular portion substantially coextensive in length with the height of said fire-pot section extending from said last named nipple 35 portion into said enlarged chamber portion of the fire-pot section and having its free end terminating adjacent the base of said fire-pot section, substantially as specified.

45 Signed at the city of New York, borough of Manhattan, in the county and State of New York, this 1st day of October, one thousand nine hundred and thirty-one.

50 CHARLES W. BRABBÉE.
BERNHARD GOERG.
